UNITED STATES PATENT OFFICE.

EDWARD T. COYAN, OF PITTSBURGH, PENNSYLVANIA.

DESIGN FOR A FLAG.

52,020.

Specification for Design.

Patented May 7, 1918.

Application filed January 12, 1918. Serial No. 211,689. Term of patent 7 years.

To all whom it may concern:

Be it known that I, EDWARD T. COYAN, a citizen of the United States, residing at Pittsburgh, in the county of Allegheny and State of Pennsylvania, have invented a new, original, and ornamental Design for Flags, of which the following is a specification, reference being had to the accompanying drawings, forming part thereof.

The figure is a plan view of a flag, showing my new design.

I claim:

The ornamental design for a flag, as shown.

EDWARD T. COYAN.

Witnesses:

JOHN F. SWEENEY,
C. J. PHILLIPS.
